UNITED STATES PATENT OFFICE.

REGINALD H. WATERS, OF CUMBERLAND, MARYLAND, ASSIGNOR TO KELLY-SPRING-FIELD TIRE COMPANY, OF NEW YORK, N. Y., A CORPORATION OF NEW JERSEY.

DESIGN FOR A TREAD FOR A VEHICLE TIRE.

Application filed August 8, 1923. Serial No. 6,980. Term of patent 14 years.

To all whom it may concern:

Be it known that I, REGINALD H. WATERS, a citizen of the United States, residing at Cumberland, in the county of Allegany and State of Maryland, have invented a new, original, and ornamental Design for a Tread for a Vehicle Tire, of which the following is a specification, reference being had to the accompanying drawing, forming a part thereof.

Figure 1 is a plan view of the design on a portion of the environment structure.

Figure 2 is a cross section through 2—2 of Fig. 1, showing the rounded-out tire casting.

I claim:

The ornamental design for a tread for a vehicle tire, as shown.
